his Attorney.

UNITED STATES PATENT OFFICE.

CHARLES ANSON FRAAYER, OF KEITHSBURG, ILLINOIS.

OIL-CAN.

SPECIFICATION forming part of Letters Patent No. 403,042, dated May 7, 1889.

Application filed August 22, 1888. Serial No. 283,480. (No model.)

To all whom it may concern:

Be it known that I, CHARLES ANSON FRAAYER, a citizen of the United States, residing at Keithsburg, in the county of Mercer and State 5 of Illinois, have invented certain new and useful Improvements in Oil-Cans; and I do hereby declare the following to be a full, clear, and exact description of the invention, such as will enable others skilled in the art to which it app- 10 pertains to make and use the same.

Figure 1 is a vertical central section of the can or vessel. Fig. 2 is a detail showing in elevation the metallic lower end of the internal and flexible tube. Fig. 3 is a detail in 15 top plan of the valve in the end of said tube.

The object of this invention is to provide a pumping attachment for an oil-can or other vessel; and the novelty consists in an oil-can or other vessel of otherwise ordinary construction having exteriorly to and above its nozzle or outlet a pumping mechanism connected and adapted to be operated in connection with a flexible tube leading to the bottom of the can, together with valves in said tube, in the 20 nozzle, and in the parts above the nozzle, and in the detail of the construction of the several parts, and in the combination with each other, and in the device as a whole, all as will now be more fully described, as well as pointed 25 out in the claims.

Having now generally stated the nature and scope of my invention, I will proceed to describe it particularly, reference being had to the accompanying drawings.

30 In the drawings, A denotes any usual or ordinary oil-can or other vessel for containing liquid, provided with a filling-opening, a, closed in any usual or ordinary way to provide a suitable vent as well as stopper. Inside 35 this can or vessel is a flexible tube, B, extending to the bottom of the can, and having at its lower end the valve C, seated in the metallic annulus D and provided with a spring, c, about its stem c'. This spring operating 40 against the bridge c², through which the stem passes, the valve is thus held normally closed. In the upper part of the can this tube B is 45 secured upon the nozzle E, which, by its screw-threaded upper end, is fixed within the lower 50 end of the tube F, which belongs to the pump-

ing and discharge apparatus. This tube F in turn is screw-threaded on its outer end and so adapted to be fitted into the mouth a² at the top of the can or vessel. Within this tube F is the valve G, seated in the upper end of the nozzle E, and normally held closed by means of the spring g about its stem g', and acting against the bridge f, through the upper end of which the spindle passes, similar to the construction shown in Fig. 3. Opening into the side of this tube F, at about its middle length and at right angles to it, is the tube H, provided at its outer end with the plunger or valve I, adapted to be operated by the piston rod or stem i. This stem passes through the screw-cap h, over the end of the tube, and can be worked by one finger of the hand, which grasps the can-handle, the forefinger resting on the curved piece h', attached to the under side of tube H, and extending 60 downward toward the handle a'. The spring L, secured at one end on the inside of tube F and at the other acting against the valve I, serves to hold said valve normally at the outer end of the chamber H. 70

On the upper end of the tube F is screwed the lower end, m, of the valve-cage M. Within this is the valve N, which seats on the upper end of the tube F, and is kept normally closed by means of the spring n about its 75 shaft n', which moves in the bridge m', similar to the construction indicated in Fig. 3.

The lower end of the discharge tube or spout O fits over the valve-cage M and is soldered thereto. Its upper end is shown as broken off. 80

This invention can be worked in the following manner: The operator or user grasps the handle a' with one hand, his forefinger engaging upon the curved finger-hold h' and his thumb resting upon the outer end of the rod i. By pushing in this rod valve or plunger I is moved toward the tube F, and its quick retraction by the operation of spring L in the pump-chamber creates a vacuum and serves to open the valve G at the upper end of the 85 flexible tube B and the valve C at its lower end, and draws upward the oil or fluid from the inside of the can or vessel. So soon as the force of this movement of the plunger has 90 been exhausted the spring g, acting on the 95

100

valve G, seats it, and thus holds within the tube or pipe F—that is, the pump-chamber—all or nearly all of the fluid or oil which has been drawn up. When the interior of the 5 pipe or tube F, which I denominate the "pump-chamber," has been filled, the succeeding inward stroke of the piston or plunger serves to force the oil or fluid upward and out through the valve N into the discharge pipe or nozzle 10 of the can or vessel. The valve C will prevent the return of the oil into the can or vessel. The valve G will act to prevent its return into the flexible tube when the plunger-rod ceases to operate, and the valve N will 15 prevent the return of oil from the discharge pipe or nozzle. The valves G and N will also serve to close air-tight the pump-chamber in tube F during the operations of the piston and plunger. The lower end of the metal 20 piece D is so made that it will afford at the bottom an opening at all times for the oil to reach the tube when the valve C is open.

Having now described my invention, what I claim is—

- 25 1. In an oil-can or like vessel, an internal flexible pipe valved at its lower end where it touches the bottom, combined with the nozzle and with a pumping mechanism above the nozzle and between it and the discharge-tube, 30 said pumping mechanism being adapted for operation by the hand grasping the can-handle.
2. In the can A, the internal flexible tube, B, having the valve C at its lower end seated 35 in the annulus D and moving on stem c', and provided with spring c, and combined with the

nozzle G and with the pumping mechanism above it.

3. In an oil-can or like vessel having above the oil-chamber a tube intermediate between 40 the nozzle and the outlet proper, and in connection therewith the vacuum-producing mechanism, consisting of the plunger I and its rod and the spring L, attached to the plunger, combined with the pipe B, having the 45 spring-closing valve C at its end, and the valves G and N, respectively situated below and above the said mechanism, substantially as described.

4. In an oil-can or similar vessel, the combination of a pumping mechanism exterior to and above the oil-chamber proper, with a flexible pipe connecting with the oil-chamber, spring-valved at its lower end, and a pumping-chamber between the nozzle and outlet or 55 spout, whereby all backflow of the oil is prevented.

5. In an oil-can or like vessel, the internal pipe, B, having spring-valve and annulus D at its lower end, the spring-valves G and N in 60 the portion above the oil-chamber, the pump-chamber F between said valves, the side tube, H, the piston I, actuated as described, the spring L in said chamber, and the outlet O, all substantially as described.

In testimony whereof I affix my signature in presence of two witnesses.

CHARLES ANSON FRAZER.
